[57] CLAIM

The ornamental design for a cap pocket hanger, as shown and described.

DESCRIPTION

FIG. 1 is a front elevational view of a cap pocket hanger showing my design;

FIG. 2 is a right side view thereof with the other side being a mirror image thereof;

FIG. 3 is a top plan view thereof;

FIG. 4 is a rear elevational view thereof; and,

FIG. 5 is a bottom plan view thereof.

The cross hatch shading which is partially shown in FIGS. 1 and 4 is understood to repeat across the entire hanger except for the eyelets and the transparent pockets.
